UNITED STATES PATENT OFFICE.

SAMUEL F. BUNKER, OF CHICAGO, ILLINOIS.

DISH CLEANER.

Application filed June 3, 1925. Serial No. 34,593.

To all whom it may concern:

Be it known that I, SAMUEL F. BUNKER, a citizen of the United States, residing at Chicago, in the county of Cook and State 5 of Illinois, have invented certain new and useful Improvements in Dish Cleaners, of which the following is a specification.

This invention relates to a dish cleaner of the kind commonly employed in scraping the refuse from dishes preparatory to washing.

The object of the invention is to so construct the scraper as to reduce the amount of rubber required for edging the scraper, and to so configure the rubber that the same 15 may be readily cut or stamped from a sheet without any appreciable amount of waste or scrap, thereby reducing the cost of the article.

Further details will appear from a description of the invention, in connection with the accompanying drawing, wherein:

Figure 1 is a side elevation of one form of the cleaner or scraper;

Fig. 2 is a view partially in section, taken at right angles to the position indicated in Fig. 1;

Figs. 3 and 4 are side elevations showing modifications in the form of the holder;

Fig. 5 is a view partly in section, showing the holder of Fig. 4; and

Fig. 6 is a detail showing the manner in which the rubber edgings are blanked from a sheet of rubber in such a way as to avoid waste.

Referring to Figures 1 and 2, the cleaner or scraper comprises a handle A terminating in a head B which is provided with a slot C into which is inserted a plate D held in place by means of a cross rivet E. The plate as shown is of generally rectangular formation, and is provided around its edges with a plurality of tongues F alternately struck in opposite directions to afford a channel for the reception of the inner edges of a rubber 45 edging G which comprises a straight cross section H and side sections I extending rearwardly from the cross section and in spaced relation to one another.

The configuration of the rubber edging is such as to afford a rectangular inner opening of a size to embrace the unbroken portion of the plate D and to bring the inner edges of the rubber lining into the channel afforded by the oppositely extending tongues F, which are braced or clamped down onto

the rubber edging in such a way as to firmly hold the same in position.

In lieu of the construction shown in Figs. 1 and 2, a handle A' and B' integrally formed from a single section of wood may 60 be employed, in which case the edges of the head will be provided with grooves or channels F', which are adapted to receive the rubber edging G, the inner edges of which abut against the unbroken or uncut portion 65 of the head B' which affords the base or bottom of the channel.

In Figs. 4 and 5, the handle A² is provided with a slotted head B² which receives a pair of abutting plates D², the edges F² 70 of which are offset in opposite directions to afford a channel for the reception of a rubber edging.

As shown in Figs. 4 and 5, each plate D² is provided with an outwardly deflected 75 socket J, which sockets, in conjunction, receive the tip end of the head B² of the handle, a rivet E² being provided to hold the parts in assembled relation. The plates D² are preferably soldered or braced together to furnish a practically integral plate structure with a channel around its edge.

As indicated in Fig. 6, the rubber edgings can be stamped from a continuous sheet or strip of rubber, by so marking off the individual units that the side sections I of one unit will be formed from the material cut out from the inner edges of the next adjacent unit, so that the waste in rubber will 90 be reduced to a minimum.

Although I have referred to a "rubber" edging, it will be understood that the term is intended to apply equally to any rubber-like material or composition which may be used for the purpose of affording a suitable scraping or squeegee surface or edging for the scraper.

I claim:

1. In a dish cleaner, the combination of a handle having on its end an enlarged holding portion provided around three of its edges with a channel and a rubberlike edging section comprising a cross strip and rearwardly extending side strips entered 100 within the cross and side portions of the channel, the edging strip having its edges outwardly protruding from the several portions of the channel, substantially as described.

100

105

110

2. In a dish cleaner, the combination of a handle terminating in a slotted head, a plate entered within the slot in the head, said plate having channels formed along its side and cross edges, and an edging of thin rubberlike material cut away in its center to embrace the plate and having its inner edges entered within the cross and side channels, and having the outer edges of the 10 edging protruding from the channels, substantially as described.

3. In a dish cleaner, the combination of a handle provided with a slotted head, a plate

entered and clamped within the slot in the head, said plate having along its cross and side edges a plurality of tongues alternately sprung in opposite directions to afford side and cross channels, and an edging of rubberlike material cut away in its center to embrace the plate and having its inner edges entered within the cross and side channels, and having the outer edges of the edging 20 protruding from the channels, substantially as described.

SAMUEL F. BUNKER.
